PAUL A. GOLLNICK AND FRANK W. BRODERICK, OF CHICAGO, ILLINOIS, ASSIGNEES,
BY MESNE ASSIGNMENTS, TO SELECTOGRAPH COMPANY, OF CHICAGO, ILLINOIS, A
CORPORATION OF ILLINOIS

PRINTING MECHANISM FOR ADDRESSING MACHINES

Application filed March 21, 1929. Serial No. 348,782.

This invention relates to printing apparatuses and particularly to printing mechanisms adapted for use in connection with addressing machines and similar devices.

5 The main objects of this invention are to provide a printing apparatus having improved means for supporting the ink applying member above the guideway along which the stencils or other forms are fed step-by-step; to provide improved operating mechanism 10 for reciprocating said supporting means so as to move said ink applying member into and out of effective engagement with the stencils; to provide an operating mechanism 15 of this kind having improved means for continuously reciprocating said supporting means between predetermined limits so as to move the ink applying member into close proximity with every one of the stencils and having other means selectively controlled for moving said supporting means beyond one of said limits for pressing the ink applying member into effective contact with the selected stencils; and to provide an apparatus 20 of this kind which is simple in construction and quiet in operation.

An illustrative embodiment of this invention is shown in the accompanying drawings, wherein:

30 Figure 1 is a top plan of an improved printing apparatus, showing also a portion of an addressing machine.

Fig. 2 is a vertical transverse section taken on the line 2—2 of Fig. 1 and showing the 35 ink applying member in its uppermost position.

Fig. 3 is a view similar to Fig. 2, but showing the ink applying member in close proximity to the stencil guideway.

40 Fig. 4 is a view similar to Figs. 2 and 3, but showing the ink applying member pressed into effective contact with a stencil.

Figs. 5, 6 and 7 are sections taken on the 45 lines 5—5, 6—6, and 7—7 respectively of Fig. 1 and showing various parts of the means which actuate the operating mechanism.

An improved printing mechanism embodying this invention is adapted for use in many different types of machines but, in the 50 specific form herein illustrated, the invention

is applied to an addressing machine. Inasmuch as this invention relates particularly to the printing mechanism, certain parts of the machine not relating thereto and believed unnecessary to a complete understanding of the invention have been omitted from the drawings.

55 In the construction herein shown, the improved printing apparatus includes an ink applying member supported on a carriage, 60 which is oscillated continuously between predetermined positions for moving the ink applying member continuously toward and from the stencils or other forms. The actuating mechanism also includes improved selectively controlled means for extending the 65 stroke of the carriage to press the ink applying member into effective contact with the stencils which are selected by the selector mechanism.

70 In the embodiment illustrated, the printing mechanism is applied to an addressing machine having a horizontal table or bed 1, on which is mounted a pair of spaced rails 2 forming a guideway for supporting and guiding a plurality of stencils 3, which are fed step-by-step through the machine so as to be operated upon by the improved printing mechanism and by various other mechanisms, not shown.

75 Located between the bed 1 and guideway 2, is a passage 4 for receiving a stack of envelopes 5 upon which the addresses are printed from the stencils. Located directly below the stencil guideway, in vertical alinement with the impression member, is a vertically movable platen or anvil 6, which is adapted to raise the stack of envelopes into position to permit the top one to receive the impression.

80 The platen 6 and its operating mechanism are more fully shown and described in the co-pending application Serial No. 347,004, filed March 14, 1929.

85 In the form shown, the printing mechanism includes an ink applying member 7 mounted on a carriage 8 pivotally supported on a frame 9 and adapted to be oscillated by improved operating mechanism 10.

90 The ink applying member 7 comprises a

95

100

roller journaled in the carriage 8 and adapted to receive ink from suitable distributing rollers, not shown.

The carriage 8 is in the form of a yoke having a pair of end members 11 connected to an integral cross brace 12. Formed on the end members 11, are bosses 13 which are journaled on bushings 14 on a shaft 15, which is supported in the frame 9 and which forms the pivot on which the carriage 8 oscillates.

The frame 9 is rigidly mounted on the bed 1 and comprises a pair of side brackets 16 and 17 and a connecting base part 18 located substantially in the plane of the guideway 2.

15 The improved operating mechanism 10 includes means 19 adapted to continuously oscillate the carriage 8 between predetermined positions and selectively controlled means 20 arranged to coact with the means 19 for extending the stroke of the carriage so as to press the roller 7 into firm contact with the selected stencils.

In the form shown, the operating means 19 comprises a drive shaft 21 geared to an eccentric 22, which actuates a toggle 23 connected to the carriage 8.

The drive shaft 21 is journaled in the brackets 16 and 17 and is continuously driven by any suitable means, not shown.

30 The eccentric 22 is journaled on a bushing 24, which embraces a fixed shaft 25 supported in the brackets 16 and 17. Integrally formed on the eccentric 22, is a pair of laterally extending sleeve parts 26 and 27, which loosely embrace the bushing 24.

35 The sleeve part 26 is geared to the drive shaft 21 by gears 28, 29 and 30. The gears 28 and 30 are fixed on the sleeve 26 and shaft 21, respectively, and the gear 29 is journaled on a stud 31 fixed on the bracket 16.

40 The toggle 23 comprises a link 32 and an arm 33 pivotally secured together by a pin 34. Supported in the outer end of the link 32, is a pivot pin 35 having a block 36 which has threaded engagement with one end of a screw 37 supported in the brace 12 of the carriage 8. The screw 37 permits adjustment of the stroke of the carriage 8 for varying the pressure of the ink applying roller 7 upon the stencil.

45 Integrally formed on the arm 33, is a sleeve or strap 38 which loosely embraces the eccentric 22 for imparting a forward and backward movement to the toggle 23 during the rotation of the eccentric so as to oscillate the carriage 8 and roller 7 between the positions illustrated in Figs. 2 and 3.

50 The selectively controlled means 20, which presses the roller 7 into contact with the selected stencils, includes a strap 39 loosely embracing an eccentric 40 fixed on a driven shaft 41. The strap 39 is pivoted to a pin 42, which is secured to an arm 43 integrally formed on the arm 33 of the operating means 19, so that, upon rotation of the eccentric 40, the pivot

pin 34 is lifted so as to extend the toggle 23 at the same time that the toggle is moved forwardly under the action of the eccentric 22.

The eccentric 40 is keyed to the shaft 41 and is secured against outward movement by a split washer 44 seated in an annular groove 45 of the shaft 41.

60 The end of the shaft 41, which supports the eccentric 40, is journaled in the bracket 16. The other end of the shaft 41 has a reduced part 46, which is journaled in a bore 47 of a stud 48 rotatably supported in an upright post 49.

65 Secured to the shaft 41, is a collar 50, which engages the bearing 16 for securing the shaft against withdrawal from the stud 48.

70 Fixed on the shaft 41, is a gear 51 meshing with a gear 52, which is fixed on a sleeve 53 loosely supported on the drive shaft 21.

75 The sleeve 53 is part of a selector mechanism which is controlled in its operation by certain indicia on the stencils. The selector mechanism is shown and described in Patent No. 1,708,268, issued April 9, 1929.

80 Fixed on the sleeve 53, is a second gear 54 which meshes with gear 55 fixed on the stud 48. The stud 48 is geared to a shaft 56, which actuates the anvil 6 by means of the intermediate mechanism shown and described in said co-pending application.

85 The gears 51, 52, 54 and 55 are mutilated, as illustrated in Figs. 1, 6 and 7 so that, during the impression operation, the anvil 6 remains at rest and, during the downward movement of the anvil, the operating means 20 is unaffected by the rotation of the sleeve 53.

90 In operation, the stencils 3 are fed step-by-step along the guideway 2, so as to position one stencil at a time below the impression roller 7.

95 During the operation of the machine, the shaft 21 rotates continuously so as to drive the roller 7 into close proximity with each of the stencils through the action of the carriage 8, toggle 23, and eccentric 22.

100 When a selected stencil approaches printing position, the sleeve 53 is rotated, so as to rotate the shaft 41 and eccentric 40. Upon rotation of the eccentric 40, the strap 39 is lifted, thereby extending the toggle 23 so as to force the ink applying roller 7 into effective contact with the selected stencil, as shown in Fig. 4.

105 Although but one specific embodiment of this invention has been herein shown and described, it will be understood that numerous details of the construction shown may be altered or omitted without departing from the spirit of this invention as defined by the following claims.

110 We claim:

115 1. A device of the class described comprising a bed adapted to support a form, an oscillating carriage on one side of said bed,

an ink applying member supported on said carriage, a toggle arranged to oscillate said carriage between predetermined positions, a driven shaft, an eccentric on said shaft, and
5 a strap embracing said eccentric and connected to said toggle for extending said toggle so as to extend the stroke of said carriage.

2. A device of the class described comprising a bed adapted to support a form, an oscillating carriage on one side of said bed, an ink applying member supported on said carriage, a rotatable shaft, an eccentric on said shaft, a sleeve embracing said eccentric, a toggle connecting said carriage with said sleeve whereby said carriage is oscillated to move said ink applying member between predetermined positions, a second shaft, an eccentric on said second shaft, and a strap embracing said second eccentric and connected
15 to said toggle for extending said toggle to extend the stroke of said carriage.

3. A device of the class described comprising a bed adapted to support a form, a reciprocable ink applying member located
25 on one side of said bed, a continuously rotated drive shaft, means actuated by said shaft for continuously reciprocating said member between predetermined positions, a sleeve embracing said drive shaft and rotatable relative thereto, a driven shaft, mated gears connecting said driven shaft with said sleeve, and means actuated by said driven shaft for extending the stroke of said ink applying member to press said member
30 into effective contact with a form.

Signed at Chicago this 19th day of March,
1929.

PAUL A. GOLLNICK.
FRANK W. BRODERICK.
